UNITED STATES PATENT OFFICE.

ALBERT F. TIMME, OF KENOSHA, WISCONSIN.

REVAPORIZER.

Application filed January 11, 1926. Serial No. 80,553.

This invention relates to improvements in revaporizers, more particularly adapted for use with internal combustion engines.

In the use of internal combustion engines, it has been found that the gasoline which is drawn through the carburetor does not thoroughly mix with the air and revaporize, with the result that liquid fuel is drawn, through the intake manifold, into the cylinders of the engine, resulting in loss of efficiency, waste of fuel and actual damage to the engine due to diluting the lubricating oil, excessive carbon formation and causing the engine to overheat.

It is one of the objects of the present invention to overcome the before mentioned objectionable features, and provide a revaporizer which will thoroughly vaporize the gasoline before it enters the intake manifold.

A further object of the invention is to provide a revaporizer which will collect and trap that portion of the fuel which passes through the carburetor in liquid form and properly mix the liquid with sufficient air to vaporize it before it reaches the cylinders of the engine.

A further object of the invention is to provide a revaporizer which is automatically operated and regulated by the suction, and variation in suction, of the engine in drawing the fuel into the cylinders of the engine.

A further object of the invention is to provide a revaporizer carburetor which will indicate to the user whether or not the main carburetor is properly adjusted to produce the most efficient results.

A further object of the invention is to provide a revaporizer carburetor in which the fuel passing through the carburetor is visible at all times.

A further object of the invention is to provide a revaporizer carburetor which automatically provides a rich mixture of fuel for starting the engine.

A further object of the invention is to provide a revaporizer carburetor which is of simple construction, is strong and durable, and is well adapted for the purposes described.

With the above and other objects in view, the invention consists of the improved revaporizer carburetor, and its parts and combinations as set forth in the claims, and all equivalents thereof.

In the accompanying drawing in which

the same reference characters indicate the same parts in all of the views:

Fig. 1 is a vertical transverse sectional view of the improved revaporizer carburetor;

Fig. 2 is a top view thereof; and

Fig. 3 is a side view of the revaporizer carburetor shown interposed between portions of a carburetor and the intake manifold of an internal combustion engine, parts being broken away and other parts being shown in section.

Referring to the drawing, the numeral 5 indicates a portion of the intake manifold of an internal combustion engine, and 6 a portion of a carburetor for vaporizing a fluid fuel and supplying the gaseous vapor to the cylinders of the engine through said intake manifold. In ordinary use, the carburetor is connected directly to the manifold, but in the present use they are spaced apart a slight distance to receive the revaporizer carburetor 7 interposed therebetween. Said revaporizer carburetor is provided with an attaching portion or flange 8, which extends between the flanges or ends of the carburetor and the intake manifold, respectively, and is connected thereto by bolts 9. The flange 8 is formed with a central opening 10 which is in register with the bores of the intake manifold and the carburetor, as clearly shown in Fig. 3. A cap member 11 is formed on the lower portion of the flange and is formed with an interior thread 12 for receiving the upper open end of a receptacle 13 preferably formed of a transparent material which will withstand heat. An elongated opening or duct 14 extends downwardly through the flange 8 from the opening 10 to the inner side of the cap 11 and a suction tube 15 extends through said opening or duct 14 and terminates at its lower end at a point about midway of the height of the receptacle. The upper end 15' of the suction tube terminates about medially of the diameter of the opening 10 and is of angular or oblique formation with relation to the length of the tube, with the oblique portion 15' extending toward the bore of the intake manifold 5. The duct 14 is of greater transverse length than the diameter of the tube, and to deflect the heavier vapor and unvaporized fuel downwardly through the opening 14, a deflector plate 16 is positioned transversely of the duct 10 on the intake manifold side of the

100

105

110

tube 15, and its upper edge portion 16' is angled toward the carburetor. This deflector 16 intercepts the liquid and heavier vaporized fluid, and directs it downwardly 5 through the duct 14 and into the transparent receptacle 13 while the lighter and properly vaporized combustible fuel flows above and around the upper end portion of the suction tube 15 to the intake manifold. An inverted 10 cup-shaped or tubular extension member 17 surrounds and is connected to the portion of the tube 15 within the receptacle at a point above the lower end of the tube. The tubular member 17 is of greater diameter than the 15 tube 15 and its lower end terminates a short distance above the bottom portion of the receptacle so that if any liquid fuel should be drawn into the extension tube, it can work up the inner sides of the tube, but will be 20 prevented from entering the lower end of the tube 15, due to the fact that at a point approximately horizontally opposite the lower end of the tube 15, all upward suction through said tube 15, upon the content of the tubular 25 member 17 ceases and at such point the upward progress of any liquid working up the inner sides of said tubular member must stop. An additional deterrent is the slower suction 30 speed in the tubular member 17 due to its diameter being greater than that of the tube 15, through which suction of the engine is communicated to the receptacle 13.

An air intake tube 18 extending through the cap 11 and downwardly into the receptacle is formed with a lower curved end portion 18' which is directed in a line tangentially to the axis of the receptacle to impart a swirling or circular motion to the fluids within the receptacle, when the receptacle is 35 subjected to suction from the intake manifold through the suction tube 15. The upper end 19 of the air tube 18 terminates adjacent the attaching flange 8.

The numeral 20 indicates the ordinary butterfly valve for controlling the carburetor.

In operation, the suction from the engine will draw the fuel from the carburetor and the lighter or properly vaporized fuel will flow over and around the upper end portion 50 of the suction tube, while the fuel in liquid form and heavier or too rich vapor will be deflected downwardly by the plate 16. Suction, increased by the obstruction in the opening 10 of the suction tube and the deflector plate, through the suction tube 15, will be created in the receptacle 13 to draw the vapor therefrom into the intake manifold of the engine. The suction or partial vacuum in the receptacle will cause air to 55 rush into the receptacle through the tube 18, and as this air is directed in a tangential path with relation to the axis of the receptacle, any liquid or vapor in the receptacle will be given a circular or swirling motion, and the 60 heavier particles will, by centrifugal force,

be caused to flow around the outer periphery of the swirling fluid.

The suction in the tube 15 and its extension 17 will draw up the lighter or properly vaporized fuel, while the heavier fuel will 70 continue to swirl and mix with the incoming air through the tube 18 until it is properly mixed, and when mixed it also will be drawn into the suction tube 15 and the intake manifold and to the engine cylinders. 75 If by chance any of the liquid fuel should be drawn into the extension tube 17, the swirling motion imparted to the liquid will cause it to work up the inner sides of the extension 17, while the lower plane of the end of the tube 15, with relation to the top of the extension, will prevent the flow of the liquid into said tube 15. In stopping the operation of the engine, the vapor in the tubular portions of the intake manifold and 80 other parts will condense and will, in addition to the liquid fuel spilled by the carburetor, flow into the receptacle, and the level will rise above the lower edge of the extension 85 17. In restarting the engine, the suction will at first draw up the unvaporized fuel which closes the lower end of the extension and form a very rich mixture for starting the engine. A further advantage 90 resides in forming the receptacle of transparent material, as the operator can watch the flow of fuel through the receptacle, and if too much of the fuel in liquid form is deposited in the receptacle, it is a clear indication that the carburetor is set for too 95 rich a mixture.

From the foregoing, it will be seen that the revaporizer is of very simple construction, and can be easily attached to an engine 100 to more thoroughly vaporize the fuel supplied thereto.

What I claim as my invention is:

1. A revaporizer comprising an attaching member for interposition between the carburetor and the intake manifold of an engine 110 and having a bore in communication with the bores of said carburetor and intake manifold, said attaching member having a depending receptacle and a duct in communication with the bore and the receptacle, a suction tube extending from the member bore into the receptacle, a deflector member within the bore of the attaching member for deflecting fluid into the duct of said attaching member, and an outside air intake means extending into the receptacle and having a lower end portion 115 extending tangentially with relation to the axis of the receptacle for directing air tangentially in a horizontal plane into the fluid within the receptacle.

2. A revaporizer comprising an attaching member for interposition between the carburetor and the intake manifold of an engine and having a bore in communication 120

with the bores of said carburetor and intake manifold, said attaching member having a depending receptacle and a duct extending from its bore to the receptacle, a suction tube 5 extending from the attaching member into the receptacle to a point adjacent the bottom portion of said receptacle, an angular deflector member within the bore of the attaching member for deflecting fluid into the duct 10 of said attaching member, and an air intake tube extending through the attaching member and into the receptacle and having a lower end portion extending tangentially with relation to the axis of the receptacle 15 for directing air tangentially in a horizontal plane into the fluid within the receptacle.

3. A revaporizer comprising a cap member provided with an attaching flange for interposition between the carburetor and the intake manifold of an engine, said flange having a bore in register with the bores of the carburetor and the intake manifold and also having a duct which extends through the lower portion of the flange and the cap 25 member, a receptacle connected to the cap member, a suction tube extending through the duct and into the receptacle and terminating at a point adjacent the bottom portion 30 of the receptacle, the upper end portion of said tube terminating centrally of the bore of the flange, a deflector member extending across the lower portion of the bore of the flange and adjacent the duct for deflecting fluid into the duct of said flange and cap and the receptacle, and an air inlet tube extending 35 through the attaching member and into the receptacle and having a lower end portion extending tangentially with relation to the axis of the receptacle for directing air tangentially in a horizontal plane into the fluid 40 within the receptacle.

4. A revaporizer comprising a cap member provided with an attaching flange for interposition between the carburetor and the intake manifold of an engine, said flange having a bore in register with the bores of the carburetor and the intake manifold and also having a duct which extends through the lower portion of the flange and the cap 45 member, a transparent receptacle connected to the cap member, a suction tube extending through the duct and into the receptacle and terminating at a point adjacent the bottom portion 50 of the receptacle, the upper end portion of said tube terminating centrally of the bore of the flange and opening in the direction of the intake manifold, a deflector member extending across the lower portion of the bore of the flange and adjacent the duct for deflecting fluid into the duct of said flange and cap, and an air inlet tube extending through the cap 55 and into the receptacle and having a lower end portion extending tangentially with relation to the axis of the receptacle for directing air tangentially in a horizontal plane into the fluid within the receptacle.

60

horizontal plane into the fluid within the receptacle.

5. A revaporizer, comprising a cap member provided with an attaching flange for interposition between the carburetor and the intake manifold of an engine, said flange having a bore in register with the bores of the carburetor and the intake manifold and also having a duct which extends through the lower portion of the flange and the cap 70 member, said cap member having a threaded portion, a transparent receptacle having a threaded connection with the cap member, a suction tube extending through the duct and into the receptacle to a point above the bottom of the receptacle, an extension tube 75 having a closed upper end connection with the suction tube above its lower end, said extension tube being of larger diameter than the suction tube and terminating at its lower end adjacent the bottom of the receptacle, the upper end portion of the suction tube terminating centrally of the bore of the flange and opening in the direction of the intake manifold, a deflector member extending 80 across the lower portion of the flange bore adjacent the duct for deflecting fluid into the duct of said flange and cap and the receptacle, and an air inlet tube extending 85 through the attaching member and into the receptacle and having a lower end portion extending tangentially with relation to the axis of the receptacle for directing air tangentially in a horizontal plane into the fluid 90 within the receptacle.

6. A revaporizer, comprising a cap member provided with an attaching flange having a bore and a duct leading from the bore downwardly through the cap member, a receptacle connected to the cap member, a suction tube 105 extending through the cap and into the receptacle and having an extension which terminates adjacent the bottom portion of the receptacle, said extension being of larger cross sectional size than the tube and connected thereto above its lower end, the upper end portion of said suction tube terminating centrally of the bore of the flange and opening towards the outlet side of the flange, a deflector member extending across 110 the lower portion of the bore of the flange and adjacent the duct for deflecting fluid into the duct of said flange and cap, and an air inlet tube extending through the cap member and into the receptacle and having 115 a lower end portion extending tangentially with relation to the axis of the receptacle for directing air tangentially in a horizontal plane into the fluid within the receptacle.

7. A revaporizer, comprising a cap member 120 provided with an attaching flange having a bore and a duct leading from the bore downwardly through the cap member, a transparent receptacle removably connected to the cap member, a suction tube extending 125 through the cap and into the receptacle and having a lower end portion extending tangentially with relation to the axis of the receptacle for directing air tangentially in a horizontal plane into the fluid within the receptacle.

through the cap and into the receptacle and terminating above the bottom portion of the receptacle and having an extension which terminates adjacent the bottom portion of the receptacle, said extension being of larger diameter than the tube and connected thereto above its lower end, the upper end portion of said tube terminating centrally of the bore of the flange and opening towards the outlet side of the flange, a deflector member extending across the lower portion of the bore of the flange and adjacent the duct for deflecting fluid into the duct of

said flange and cap, the upper portion of said deflector extending towards the inlet side of the flange, and an open ended air inlet tube extending through the cap member and into the receptacle and having a lower curved end portion extending tangentially with relation to the axis of the receptacle for imparting a swirling motion in a horizontal plane to fluid within the receptacle.

In testimony whereof, I affix my signature.

ALBERT F. TIMME.
